UNITED STATES PATENT OFFICE.

ROBERT ADAMS, OF SOUTHWARK, COUNTY OF SURREY, ENGLAND.

PNEUMATIC DOOR-CHECK.

SPECIFICATION forming part of Letters Patent No. 397,326, dated February 5, 1889.

Application filed July 23, 1888. Serial No. 280,725. (No model.) Patented in England February 21, 1887, No. 2,685.

To all whom it may concern:

Be it known that I, ROBERT ADAMS, a subject of the Queen of Great Britain, residing at 17 Blackman Street, Southwark, in the 5 county of Surrey, England, engineer, have invented certain new and useful Improvements in Door-Closing Appliances and Checks for the Same, (for which I have obtained a patent in Great Britain, No. 2,685, bearing 10 date February 21, 1887,) of which the following is a specification.

The object of my invention is to provide an improved apparatus for closing doors and checking such closing to prevent slamming, 15 such closing and checking apparatus being capable of adjustment and application to their respective purposes either separately or together or in combination with other door springs and checks.

20 And in order that my said invention may be particularly described and ascertained, reference is hereby made to the accompanying drawings, in which similar letters of reference indicate corresponding parts.

25 Figure 1 is an elevation, and Figs. 2 and 3 horizontal sections, showing one method of applying my invention to the inside of the door. Figs. 4, 5, and 6 illustrate the manner of applying the invention to the outside of a 30 door. Figs. 7 and 8 show the links e^2 and f' of Figs. 1, 2, and 3 elongated and their attaching-plates placed farther apart.

In Figs. 1 and 2 the door a is shown closed and in Fig. 3 it is shown open. The door a 35 is hinged at b .

c is the lintel or transom, to which the barrel d is fixed by the bracket z , as shown.

e is an arm fixed to the door by the plate e' . The link e^2 is pivoted to the arm e .

40 f is a plate screwed to the transom, having a double link, f' , pivoted thereto.

g is a vibrating piston-rod, forming a connecting-rod between the piston inside the cylinder or barrel d and the pivot h .

45 The ends of the links e^2 and f' and the end of the piston-rod g are united at h by a screw or rivet, upon which they respectively pivot. When the door is in a closed position, as shown in Figs. 1 and 2, the leverage of the combination is at or near its most advantageous po-

sition, and as the door is opened the leverage decreases, as shown in Fig. 3, where the joint h is shown much nearer to the transom than in Fig. 2.

Fig. 4 is an elevation, and Figs. 5 and 6 55 horizontal sections, showing a method of applying my invention to the outside of the door. In this arrangement the barrel d is screwed to the door by the bracket z , and the plate f and double link f' are also fixed to the door. 60 i is a plate fixed to the transom, to which the arm k is pivoted. The form of this arm k is clearly shown in Fig. 4 and its direction with respect to the links f' in Figs. 5 and 6. The junction of the piston-rod g with the arm k is 65 a short distance from the end of the link f' . The leverage in this arrangement also decreases as the door opens, as shown in Fig. 6.

Fig. 7 is a horizontal section showing an arrangement in which the lower link, f' , and 70 the link e^2 are elongated and the plates f and e' are placed farther apart. With this exception, the arrangement is similar to that shown in Figs. 1, 2, and 3.

Fig. 8 is an elevation of the plate f and links 75 f' , f^2 , and e^2 , showing the method of construction.

Instead of placing the usual spring in the barrel, I sometimes place a coiled spring in or near the position shown by the dotted circle 80 l , Fig. 7, such spring acting upon the links f' or upon the pivot or axle, to which it is fixed by suitable connections.

o is the inlet-valve for the air, and p is the outlet-valve, which is regulated by a screw, as 85 usual in the construction of air-checks.

The relative sizes, forms, and methods of constructing the joints and brackets may be varied to suit the different positions and fittings of the door. In some cases I find it 90 advantageous to fit an additional link, as shown by a dotted line at r in Fig. 2, the end of which works in a slotted bracket, s . (Shown also in dotted lines.)

The brackets f and z and their mode of connection with the cylinder and frame may be otherwise constructed, so as to be more suitable for fixing to very narrow transoms and rails.

Having now particularly described and as- 100

certained the nature of my said invention and in what manner the same is to be performed, I declare that what I claim is—

In a door closing and checking device, the 5 combination, with the cylinder, the vibratory piston-rod, and a single-armed link, of the pivoted double-armed link $f'f'$, connected to the piston-rod and single-armed link, one of said links being attached to the door and the

other to the door-frame, substantially as de- 10 scribed.

ROBERT ADAMS.
